UNITED STATES PATENT OFFICE.

GEORGE W. DAUM, OF JEANNETTE, PENNSYLVANIA, ASSIGNOR TO PENNSYLVANIA RUBBER COMPANY, OF JEANNETTE, PENNSYLVANIA, A CORPORATION OF PENNSYLVANIA.

DESIGN FOR A VEHICLE TIRE.

Application filed November 27, 1923. Serial No. 7,895. Term of patent 14 years.

To all whom it may concern:

Be it known that I, GEORGE W. DAUM, a citizen of the United States, residing at Jeannette, county of Westmoreland, and State of Pennsylvania (whose post-office address is 303 North Second Street, Jeannette, Pennsylvania), have invented a new, original, and ornamental Design for Vehicle Tires, of which the following is a specification, reference being had to the accompanying drawing, forming part thereof.

Figure I is a plan view of the tread sur-

face of the tire showing my new design; and

Figure II is a view of the tire in side elevation.

I claim:

The ornamental design for a vehicle tire, as shown.

GEORGE W. DAUM.
